CLAIM

The ornamental design for a pipe fitting apparatus, as shown and described.

DESCRIPTION

FIG. 1 is a perspective view of a pipe fitting apparatus according to one embodiment of the present design;

FIG. 2 is a side view of a pipe fitting apparatus according to one embodiment of the present design;

FIG. 3 is an end view of a pipe fitting apparatus according to one embodiment of the present design;

FIG. 4 is an end view of a pipe fitting apparatus according to one embodiment of the present design;

FIG. 5 is a top view of a pipe fitting apparatus according to one embodiment of the present design;

FIG. 6 is a bottom view of a pipe fitting apparatus according to one embodiment of the present design;

FIG. 7 is a perspective view of a pipe fitting apparatus according to one embodiment of the present design;

FIG. 8 is a side view of a pipe fitting apparatus according to one embodiment of the present design;

FIG. 9 is an end view of a pipe fitting apparatus according to one embodiment of the present design;

FIG. 10 is an end view of a pipe fitting apparatus according to one embodiment of the present design;

FIG. 11 is a top view of a pipe fitting apparatus according to one embodiment of the present design;

FIG. 12 is a bottom view of a pipe fitting apparatus according to one embodiment of the present design;

FIG. 13 is a side view of a pipe fitting apparatus according to the embodiment of FIGS. 1-6 and FIGS. 7-12 of the present design; and,

FIG. 14 is a side view of a pipe fitting apparatus according to the embodiment of FIGS. 1-6 and FIGS. 7-12 of the present design.

The broken lines indicating threads are shown for illustrative purposes only and form no part of the claimed design.
